UNITED STATES PATENT OFFICE.

JOHN J. GWYNN, OF PLAINFIELD, NEW JERSEY.

LAMP.

Specification of Letters Patent No. 33,140, dated August 27, 1861.

To all whom it may concern:

Be it known that I, JOHN J. GWYNN, of Plainfield, in the county of Union, State of New Jersey, have invented certain new and 5 useful Improvements in Burners for Kerosene and other Glass-Chimney Lamps and Gas-Burners; and I do hereby declare that the following is a full and correct description thereof, reference being had to the annexed drawings, forming part of this specification, and to the letters of reference thereon.

Figure 1, is a vertical section of a common kerosene burner with this improvement attached. Fig. 2 is a vertical section of a common kerosene burner with this improvement attached. Fig. 3 is a vertical section of a common kerosene burner with this improvement attached. Fig. 4 the "pawl" 10 or "click" detached. Fig. 5 modified form of the same. Fig. 6 showing another mode of suspension.

A Fig. 1 is the "cap" or "deflector" on which the glass rests.

25 B Fig. 1 is the "pawl" or "click".

C Fig. 1 is the pin or points on which the "pawl" B is suspended.

Letters A. B. and C. Fig. 2 same as above last mentioned only illustrating the modified 30 "pawl" Fig. 5 in action.

A and B, Fig. 3 is the same as before.

C Figs. 3 and 6, is the suspension wire longer than in Figs. 1 and 2, and so curved as to stand directly over the serrated rim or 35 "gallery" of the burner, the points or ends of the wire being fastened thereto, and thus permitting, by the flexible wire, a slight vertical play of the "pawl" that it may accommodate a thick or thin edged glass.

40 The nature of my invention, is an appliance, for the purpose of securing the glass over a lamp or other burner which shall accommodate the expansion of the glass when the burner is lighted.

45 For the purpose of enabling others skilled in the art, to make and use my invention I will proceed to describe its construction and operation.

It will be observed in the form of the 50 "pawl" B, that when suspended, the pre-

ponderating weight being on the outside of the point of suspension, that in its endeavor to balance itself on pin C, Fig. 1, it will intrude itself in the inside of the "gallery" far enough to take all the hold on the rim 55 of the glass that its form will permit. Now any form of "pawl" made to act on this principle and suspended in the manner shown in Fig. 1, or in any other convenient manner, is in its action automatic, as hereafter shown in describing the manner of using the same.

It will be observed that in Fig. 5 the form of the pawl is modified, the tip or toe being thinner so that it may spring a little to accommodate a thick edged glass.

The operation of this appliance is simply thus, the glass is leaned over so as to put one edge under the lugs or points cut in the edge of the "gallery" for that purpose, opposite the "pawl" or click and by pressing down the glass onto the cap A, the "pawl" recedes, and by the weight on the outside of the point of suspension (when the glass is pressed down) the "pawl" advances and 75 thus secures the glass of its own action. It will be further observed that if you endeavor to remove the glass when secured the hold of the "pawl" becomes more positive, and the glass is held more firmly for the 80 reason that the strain is altogether on the inside of the point of suspension, and is resisted by the suspending wire. To remove the glass, is simply to put one finger under the "pawl" on the outside of the "gallery" 85 and by pushing it upward the "pawl" recedes from the glass, which can then be removed.

I do not claim any part of the construction of the burner as shown.

90 What I claim and desire to secure by Letters Patent is—

The suspended pawl or click fastening, in combination with any form of glass chimney or any other burner substantially and for 95 the purpose set forth.

JOHN J. GWYNN.
